COMBINED DIAL FACE AND HANDS FOR A GAME TIMING CLOCK

Alfred H. Keast, San Francisco, Calif.

Application August 20, 1956, Serial No. 42,666

Term of patent 14 years

(Cl. D42—1)

Fig. 1

Fig. 2

Fig. 1 is a front elevational view of a combined dial face and hands for a game timing clock; and

Fig. 2 is a side elevational view thereof.

I claim the ornamental design for a combined dial face and hands for a game timing clock, as shown.
